UNITED STATES PATENT OFFICE.

HERMAN L. WITTSTEIN, OF NEW HAVEN, CONNECTICUT, ASSIGNOR TO THE ATLAS MANUFACTURING COMPANY, OF NEW HAVEN, CONNECTICUT, A CORPORATION OF CONNECTICUT.

KNIFE SHARPENER.

Application filed February 2, 1925. Serial No. 6,331.

To all whom it may concern:

Be it known that I, HERMAN L. WITTSTEIN, a citizen of the United States, residing at New Haven, in the county of New Haven and State of Connecticut, have invented certain new and useful Improvements in Knife Sharpeners, of which the following is a specification, reference being had therein to the accompanying drawings.

This invention relates to a new and improved knife sharpener and it is the object thereof, among other things, to so simplify the structure of such a device that it may be produced from the minimum amount of metal, the fastening portion thereof arranged substantially parallel with the axis of the sharpening rolls and the space below the rolls being open and accessible for purposes of cleaning, etc.

The details and arrangement of the parts of my improved knife sharpener will be apparent from an inspection of the accompanying drawings, in connection with the description hereinafter contained, and wherein in a preferred embodiment of the invention is disclosed for the purpose of imparting an understanding of the same.

In the drawings, wherein like characters of reference designate like parts in the several figures;

Figure 1 is a side elevation of my new and improved knife sharpener;

Figure 2 is a plan view thereof; and

Figure 3 is a transverse sectional view thereof, taken generally upon line 3—3 of Figure 2.

As herein described; 10 designates the base portion of the standard; 11 the substantially parallel side portions; and 12 the foot portions, which project laterally from each side of the base portion, and each having an opening 13 therethrough for a fastening device or the like.

Rotatably mounted upon the pins 14, fixed in the side portions 11, are the sharpening rolls 15 and spacing washers 16, the peripheries of the rolls overlapping slightly, as is usual.

The standard is preferably, but not necessarily made of sheet metal and the openings 17 in the side portions 11, from which the foot portions 12 are formed, leave an open space underneath the overlapping peripheries of the rolls that is accessible for cleaning purposes.

The location of the fastening apertures 13 is such that the sharpener may be secured by fastening elements that are substantially in a line parallel with the pins 14 and the direction of movement of the article being sharpened while in contact with the sharpening rolls.

With this knife sharpener the passing of a cloth or the like through the openings 17 and underneath the rolls 15, will remove any accumulated foreign matter.

What I claim as new and desire to secure by Letters Patent, is:—

A knife sharpener composed of a flat base of relatively considerable length and width, parallel sides extending upwardly from the base and having openings of a size to readily admit a cleaning cloth, a pair of pins carried by the sides and extending transversely of the base, rolls carried by the pins, and lateral feet extending outwardly from the sides of the base and having openings to receive fastenings, said feet being disposed in the plane of the base and said rolls being spaced a distance above the base, whereby to enable cleaning of the base by movement of a cloth laterally of the base and through the openings of the sides and beneath the rolls, the ends of the sides terminating at the sides of the base so as to enable a cloth to be moved longitudinally of the base and beneath the rolls, the rolls being overlapped in a line coextensive with a line bisecting the feet, so as to cause the sharpening movements of the knife to occur in the vertical plane in which the last mentioned line lies.

In testimony whereof, I have hereunto affixed my signature.

HERMAN L. WITTSTEIN.
